UNITED STATES PATENT OFFICE.

SWEN BERGLING AND KARL ANDERSON, OF CHICAGO, ILLINOIS, ASSIGNORS TO RELIABLE HOIST COMPANY, OF CHICAGO, ILLINOIS, A CORPORATION.

HOIST.

Application filed June 15, 1925. Serial No. 37,049.

Our invention relates to improvements in hoists especially adapted for use in building operations or the like, the object of the invention being to provide a simple, durable and efficient apparatus of this character.

Other objects will appear hereinafter.

The invention consists in the combinations and arrangements of parts hereinafter described and claimed.

The invention will be best understood by reference to the accompanying drawings, forming a part of this specification and in which,

Fig. 1 is a side view of a portion of a hoisting apparatus embodying the invention;

Fig. 2 a top plan view corresponding with Fig. 1;

Fig. 3 a horizontal section taken substantially on line 3—3 of Fig. 1;

Fig. 4 a vertical section taken substantially on line 4—4 of Fig. 1;

Fig. 5 a partial view taken substantially on line 5—5 of Fig. 3;

Fig. 6 a detail section taken substantially on line 6—6 of Fig. 5;

Fig. 7 a partial elevation of a pair of elevators and their shafts arranged for operation by the hoist;

Fig. 8 a view at right angles to Fig. 7; and

Fig. 9 a top plan view of the elevator shaft.

The preferred form of construction as illustrated in the drawings comprises a suitable frame 10 having a gear casing 11 mounted thereon. Arranged in the gear casing 11 are two axially aligning winding shafts 12 and 13, the shaft 12 carrying a winding drum 14 and the shaft 13 carrying a winding drum 15. A hoisting cable 16 is partially wound upon the drums 14 and 15, said cable being passed over guide pulleys 17 between said drums so as to permit of the free travel of said hoisting cable from one drum to the other. Each of the guide pulleys 17 is arranged with its guide grooves substantially tangential to the corresponding winding drum and said guide pulleys are also arranged tangentially to each other. In this way a simple and effective guide for the hoisting cable from one drum to the other is provided which can be arranged in small space, which permits of

wide separation of the hoisting drums, and which will adequately guide the hoisting cable during operation. As will be noted the hoisting cable 16 is similarly wound on each drum so that rotation of the drums 14 and 15 in the same direction will cause winding up and retraction of the corresponding end of the hoisting cable.

The shafts 12 and 13 are provided at their inner ends with enlarged bearing heads 18 and an operating shaft 19 is mounted in the bearings in said bearing heads, the shafts 12, 13 and 19 being thus mounted in axial alignment with each other. The operating shaft 19 carries a central driving gear 20 and clutch members 21 and 22 are arranged on the opposite sides of the hub of said driving gear as best shown in Fig. 4. Corresponding shiftable clutch members 23 and 24 are splined on the corresponding shaft heads 18 and whereby said clutch members 23 and 24 may be shifted into and out of engagement with the clutch members 21 and 22 so as to drive either of the shafts 12 or 13 and release the other. As best shown in Fig. 3 the clutch members 23 and 24 are operatively connected with rocker arms 25 and 26 secured to vertical rocker shafts 27 and 28 which are extended through the top of the gear casing 11. As best shown in Fig. 2 the upper ends of the shafts 27 and 28 carry rocker arms 29 connected by a link 30 compelling simultaneous operation of said rocker shafts and consequently of the clutch members 23 and 24 in opposite directions. Shaft 28 carries a rocker arm 31 connected by a link 32 with a rocker arm 33 on the upper end of a rocker shaft 34 extending vertically adjacent one end of the gear casing 11. The rocker arm 34 carries an operating lever 35 for rocking the same. As best shown in Figs. 5 and 6 the lever 35 carries a double acting cam head 36 which is in substantially inverted V-form and normally engages a corresponding recess in a cam block 37 mounted on rocker arms 38 secured to a transverse rocker shaft 39. The rocker shaft 39 carries at its opposite ends rocker arms 40 connected by links 41 with brake bands 42 engaging brake drums 43 on the winding drums 14 and 15. As best shown in Fig. 2 the operating lever 35 is connected with an operating cable 44 passing over guide pulleys 45 and whereby said operating lever may be shifted in either di-

rection to rock the shaft 35 to correspond. As the lever 35 shifts in either direction the cam head 36 operating on the cam block 37 raises the rocker arms 38 to rock the rocker shaft 39 upwardly, thus simultaneously releasing the brake bands 42 from the brake drums 43. Each of the brake bands 42 is anchored by the link 46 to a corresponding post or abutment 47 on the frame 10 and the rocker shaft 39 is provided with a depending rocker arm 48 connected with a tension spring 49 adjustably secured by a rod 50 to a post or abutment 51 on the frame 10. By this arrangement it will be observed that the brake bands 42 will be normally held in operative engagement with the brake drums 43 by the spring 49 but that upon shifting of the lever 35 in either direction said brake bands will be released thus freeing the corresponding winding drums.

As best shown in Fig. 3 the driving gear 20 is connected with a pinion 52 on a shaft 53 connected by a gear 54 with a pinion 55 on shaft 56. The shaft 56 is connected by a gear 57 with a pinion 58 on shaft 59 of the motor 60 as best shown in Figs. 1 and 2. The motor 60 is operated to keep the driving gear 20 constantly rotating in the same direction but at relatively slower speed. It will be noted that by shifting the cable 44 in either direction the corresponding drum 14 or 15 as the case may be will be operated to wind up or retract the corresponding end 33 of the hoisting cable 16 and pay out the other end thereof and that when said operating cable is shifted back to normal position the operation of both drums will cease and the corresponding brake bands automatically applied to stop the movement of the hoisting cable. The ends of the hoisting cable 16 are passed over suitable guide pulleys as best shown in Figs. 7, 8 and 9 and connected with the elevator cages 61 operating in elevator shafts 62 in the usual way. The ends of operating cable 44 are similarly passed over suitable guide pulleys and also over the operating pulley 63 at the top of the elevator shafts and mounted on a rocker shaft 64 as shown, the ends of the cable 44 being joined together. The rocker shaft 64 carries a rocker lever 65 to the opposite ends of which are connected depending operating cables 66 and whereby the pulley 63 may be oscillated in either direction to cause corresponding operation of the operating cable 44 and corresponding operation of the lever 35 to start, stop and reverse the hoisting mechanism to control the operation of the elevator cages 61 as will be readily understood. Adjustable stop blocks 67 are mounted on the cable 44 and the cable 44 is run through stop blocks 68 on the elevator cages 61 and whereby by adjusting the stop blocks 67 properly the elevator cages will be caused

to automatically stop at any selected or convenient elevation as will be readily understood.

The construction disclosed is a simple and efficient hoisting apparatus especially adapted for use in building operations and the like which may be readily controlled manually from any desired location and which will automatically stop the cages at any desired elevation.

While we have illustrated and described the preferred form of construction for carrying our invention into effect, this is capable of variation and modification without departing from the spirit of the invention. We, therefore, do not wish to be limited to the precise details of construction set forth but desire to avail ourselves of such variations and modifications as come within the scope of the appended claims.

Having described our invention, what we claim as new and desire to secure by Letters Patent is:

1. A hoist comprising two axially aligning winding shafts; winding drums on said shafts; an operating shaft between said winding shafts and axially aligning therewith; a driving gear and double clutch member on said operating shaft; a shiftable clutch member on each of said winding shafts independent of the corresponding drum; means for shifting said shiftable clutch members alternately into and out of engagement with said double clutch; and a hoisting cable partially wound on said drums, substantially as described.

2. A hoist comprising two axially aligning winding shafts; winding drums on said shafts; an operating shaft between said winding shafts and axially aligning therewith, there being bearings formed in the adjacent ends of said winding shafts and said operating shaft being mounted in said bearings; a driving gear and double clutch member on said operating shaft; a shiftable clutch member on each of said winding shafts; means for shifting said shiftable clutch members alternately into and out of engagement with said double clutch; and a hoisting cable partially wound on said drums, substantially as described.

3. A hoist comprising two axially aligning winding shafts; winding drums on said shafts; an operating shaft between said winding shafts and axially aligning therewith; a driving gear and double clutch member on said operating shaft; a shiftable clutch member on each of said winding shafts; means for shifting said shiftable clutch members alternately into and out of engagement with said double clutch; guide pulleys arranged between said drums; and a hoisting cable partially wound on said drums and passing over said guide pulleys, substantially as described.

4. A hoist comprising two axially aligning winding shafts; winding drums on said shafts; an operating shaft between said winding shafts and axially aligning therewith, there being bearings formed in the adjacent ends of said winding shafts and said operating shaft being mounted in said bearings; a driving gear and double clutch member on said operating shaft; a shiftable clutch member on each of said winding shafts; means for shifting said shiftable clutch members alternately into and out of engagement with said double clutch; guide pulleys arranged between said drums; and a hoisting cable partially wound on said drums and passing over said guide pulleys, substantially as described.

5. A hoist comprising two axially aligning winding shafts; winding drums on said shafts; an operating shaft between said winding shafts and axially aligning therewith; a driving gear and double clutch member on said operating shaft; a shiftable clutch member on each of said winding shafts; means for alternately shifting said shiftable clutch members into and out of engagement with said double clutch and releasing the other winding shaft for reverse operation; and a hoisting cable partially wound on said drums, substantially as described.

6. A hoist comprising two axially aligning winding shafts; winding drums on said shafts; an operating shaft between said winding shafts and axially aligning therewith; a driving gear and double clutch member on said operating shaft; a shiftable clutch member on each of the winding shafts; a brake for each of said drums; means for alternately shifting said clutch members to cause positive operation of one of said drums and release of the other drum for reverse operation and simultaneous release of said brake; and a hoisting cable partially wound on said drums, substantially as described.

7. A hoist comprising two axially aligning winding shafts; winding drums on said shafts; an operating shaft between said winding shafts and axially aligning therewith; a driving gear and double clutch member on said operating shaft; a motor; a reducing chain of gears connecting said motor with said driving gear; a shiftable clutch member on each of said winding shafts; a brake for each of said drums; means for alternately shifting said shiftable clutch members into and out of engagement with said double clutch and simultaneously releasing said brakes; and a hoisting cable partially wound on said drums, substantially as described.

8. A hoist comprising two axially aligning winding shafts; winding drums on said shafts; an operating shaft between said

winding shafts and axially aligning therewith; a driving gear and double clutch member on said operating shaft; a motor; a reducing chain of gears connecting said motor with said driving gear; a shiftable clutch member on each of said winding shafts; a brake for each of said drums; means for alternately shifting said shiftable clutch members into and out of engagement with said double clutch and simultaneously releasing said brakes; a hoisting cable partially wound on said drums; and an operative connection between said hoisting cable and the means for shifting said clutch members and releasing said brakes arranged to automatically shift said clutch members and release said brakes at predetermined points of operation of said cable, substantially as described.

9. A hoist comprising two axially aligning winding shafts; winding drums on said shafts; an operating shaft between said winding shafts and axially aligning therewith; a driving gear and double clutch member on said operating shaft; a shiftable clutch member on each of said winding shafts and arranged to be shifted into and out of engagement with the corresponding double clutch member on said operating shaft; rocker shafts operatively connected with said shiftable clutch member; an operative connection between said rocker shafts compelling simultaneous operation thereof; manually operable means for operating said rocker shafts to shift said clutch members into and out of engagement with said double clutch member; and a hoisting cable partially wound on said drums, substantially as described.

10. A hoist comprising two axially aligning winding shafts; winding drums on said shafts; a hoisting cable partially wound on said drums; an operating shaft between said winding shafts and axially aligning therewith; a driving gear and double clutch member on said operating shaft; a shiftable clutch member on each of said winding shafts and shiftable into and out of engagement with said double clutch member; a brake drum operatively connected with each of said winding drums; a brake band for each of said drums; a pair of interconnected rocker shafts operatively connected with said shiftable clutch members; a rocker shaft operatively connected with said brake bands; a spring normally holding said brake bands in engagement with their drums; and manually operable means for simultaneously operating said rocker shafts to shift said shiftable clutch members and release said brake bands, substantially as described.

11. A hoist comprising two axially aligning winding shafts; winding drums on said shafts; a hoisting cable partially wound on said drums; an operating shaft between said

winding shafts and axially aligning therewith; a driving gear and double clutch member on said operating shaft; a shiftable clutch member on each of said winding shafts and shiftable into and out of engagement with said double clutch member; a brake drum operatively connected with each of said winding drums; a brake band for each of said drums; a pair of interconnected rocker shafts operatively connected with said shiftable clutch members; a rocker shaft operatively connected with said brake bands; a spring normally holding said brake bands in engagement with their drums; a third rocker shaft operatively connected with said clutch shifting rocker shafts; a lever arm for operating said third rocker shaft; a double acting cam head on said lever arm; a rocker arm on said brake operating rocker shaft carrying a cam block cooperating with said cam head on said

lever arm for operating said brake rocker shaft; and an operating cable operatively connected with said lever arm, substantially as described. 25

12. A hoist comprising two axially aligning drums; guide pulleys between said drums; a hoisting cable partially wound on said drums and extending over said guide pulleys; clutch mechanism for rotating each of said drums and releasing the other; brake mechanism for each of said drums; a spring normally applying said brake mechanisms; an operating cable; and means operable by said operating cable for simultaneously shifting said clutch mechanisms to operate either of the said drums and release said brake, substantially as described. 30 35

In testimony whereof we have signed our names to this specification.

SWEN BERGLING.
KARL ANDERSON.
